A. D. DAILEY, OF TERRE HAUTE, INDIANA.

Letters Patent No. 89,203, dated April 20, 1869.

IMPROVEMENT IN FIRE-PLACES.

The Schedule referred to in these Letters Patent and making part of the same.

To all whom it may concern:

Be it known that I, A. D. DAILEY, of Terre Haute, in the county of Vigo, and State of Indiana, have invented a new and useful Improvement in Hearth and Back-Plates of Franklin Stoves and Fire-Places; and I do hereby declare that the following is a full, clear, and exact description of the same, reference being had to the annexed drawings, making part of this specification, in which—

Figure 1 is a perspective view, and

Figure 2 is a vertical transverse section.

The same letters in both the figures indicate identical parts.

My improvement relates to the form of the back-plates of Franklin stoves and fire-places; and consists in constructing a cast-iron hearth-plate, with a fillet cast on the upper face, which, while strengthening the plate, serves also as a fender to prevent the escape of the coals, said fillet being so inclined on its front or outer face as not to prevent sweeping over it.

In the annexed drawings—

A is the hearth-plate, made of cast-iron, and having a fillet, B, raised on its upper face, curved, as shown, and extending from jamb to jamb.

This fillet, by strengthening the plate, permits the latter to be made thinner than would be otherwise practicable.

The face nearest the fire-place is nearly vertical, so as to prevent the coals from rolling out on to the floor.

The outer or front face is inclined at an acute angle,

so that a broom may be used to sweep over the fillet into the fire-place.

The hearth is intended to be set on a stone or brick bed, and flush with the floor of the room.

The back-plate, C, is formed as shown, extending across the fire-place. The lower part, from C¹ to C², is vertical. This part is extended upward to about the top of the burning fuel, as in ordinary use.

The portion from C² to C³ is constructed on the line of a parabolic curve, that from C³ to C⁴ is vertical, and that from C⁴ to C⁵ is inclined to the rear, extending behind the uptake D.

The advantage of giving to the portion between C² and C³ the parabolic form is, that rays of heat passing from the fire placed in the focus of the parabola, will be reflected therefrom in parallel and horizontal lines, according to the well-known rule governing reflection from such curves.

What I claim as my invention, and desire to secure by Letters Patent, is—

As an article of manufacture, a cast-iron hearth-plate, constructed with a fillet, B, formed substantially as set forth.

In testimony whereof, I have signed my name to this specification in the presence of two subscribing witnesses.

A. D. DAILEY.
